(Model.)

J. B. WALLACE & G. MYERS.
VAPOR BURNER.

No. 295,315.

Patented Mar. 18, 1884.

UNITED STATES PATENT OFFICE.

J. BENNETT WALLACE AND GARSON MYERS, OF CHICAGO, ILLINOIS.

VAPOR-BURNER.

SPECIFICATION forming part of Letters Patent No. 295,315, dated March 18, 1884.

Application filed January 25, 1883. (Model.)

To all whom it may concern:

Be it known that we, J. BENNETT WALLACE and GARSON MYERS, citizens of the United States, residing at Chicago, in the county of Cook, in the State of Illinois, have invented 5 certain new and useful Improvements in Vapor-Burners, which are fully set forth in the following specification, reference being had to the accompanying drawings, in which—

10 Figure 1 is a front elevation of a vapor-burner having our improvements. Fig. 2 is a rear elevation of the same, the handle of the needle-valve being broken away, and the cap of the burner being in section. Fig. 3 is a 15 bottom plan view of the base-plate of the burner and the parts included in the same casting. Fig. 4 is a top plan view of the same. Fig. 5 is a top plan view of the mixing-tube and the conducting-shield. Fig. 6 is a rear 20 elevation of the same. Fig. 7 is a vertical longitudinal section, showing the needle-valve, the adjoining part of the vaporizing-tube, and the drip-cup.

The same letters denote the same parts in 25 all the figures.

Our invention relates to apparatus for the development and combustion of hydrocarbon vapor for heating purposes, and more particularly to apparatus of the general construction shown in the patent of Zebulon Davis, 30 No. 237,826, issued February 15, 1881; and it consists in the several devices and combinations of devices, which will be fully set forth hereinafter, and definitely pointed out in the 35 claims, the object being to enhance economy of the construction and promptness and certainty of operation.

In the drawings, A denotes the base-plate of the burner, and A' the perforated cup.

40 We cast the head B' of the main oil-pipe B of the vaporizing-tube C (which leads from the head of the oil-pipe) and the seat C' of the needle-valve G all in one piece. As hereshown, they are of the same piece, with the base- 45 plate of the burner. That part of the vaporizing-tube which is between the margin of the base-plate and the needle-valve seat is cast straight, and after being drilled, to form a passage for the liquid or vapor, is bent downward 50 in a uniform curve, as shown in Figs. 1, 2, and 7. We are thus enabled to avoid the use of

one screw-plug, and, by a slight wrenching of the lower part of the tube, to restore the alignment of the jet-orifice c with the mixing-tube D, should it ever be accidentally set awry—a 55 correction which is impracticable with the conformation shown in the patent referred to, but very easy with that now shown.

The screw-plug E, which closes the lower end of the vaporizing-tube, extends far enough 60 below it to form a support for the drip-cup E', and is preferably integral therewith, as shown in Fig. 7. The plug may, however, be passed up through a hole in the bottom of the cup, so that the cup rests on the enlargement e, and 65 the two then welded together. By thus making the plug to support the cup, an appreciable economy in manufacture is effected.

The mixing-tube D is a separately-formed curved tube, whose upper end passes through 70 a central circular hole in the base-plate of the burner, just large enough to allow the tube to turn within it. An annular collar, d, is formed on the tube, the upper surface of which collar is smooth, so as to turn readily against the 75 lower surface of the base-plate. A washer or thimble, D', screwed or otherwise fastened on the tube D above the base-plate, and having a smooth under surface in contact with the plate, co-operates with the collar d to hold the 80 tube in place. The base-plate is preferably thickened around the central aperture, so as to give a better bearing for the tube to turn in.

The deflecting-shield F (whose office is to direct a diminished current of gas or a flame to the 85 under surface of the base-plate and the adjacent part of the vaporizing-tube, and thus keep the burner hot while the gas is shut off from its interior) is in our construction affixed to one side of the mixing-tube, so as to turn with it. A 90 perforated ear, f, projecting backward from the shield F, admits a lug, d', projecting laterally from the mixing-tube, to pass through it, which, being headed down upon the ear, holds the shield in place. By this means a single motion turns the mixing-tube out of line with the gas-jet and brings the shield into line with it.

The edge of the collar d is provided with a notch, d'', within which projects a stop, a, formed on the lower surface of the base-plate 100 A, for the purpose of properly limiting the rotary movement of the tube D in bringing the

said tube or the shield into or out of line, as just described. Said tube and shield are turned by the handle D², projecting from the mixing-tube on the side opposite that to which the shield is attached.

5 The shield F is preferably made tubular in its upper part; or it may, if desired, be tubular throughout its length, as shown.

The device which we have described for 10 turning the mixing-tube and the conducting-shield together is considerably more economical than the former construction, by which the shield is provided with a separate pivotal bearing, on which it turns in front of the mixing-tube; and the operation of changing the 15 direction of the gas-current is shorter and more certain, the range of shifting being equal only to the distance from the axis of the mixing-tube to that of the shield. Moreover, the 20 mouth of the mixing-tube can, in the construction set forth, be brought as near to the jet-orifice as may be found desirable, since it is unnecessary to leave room for the shield between them.

25 What we claim as our invention, and desire to secure by Letters Patent, is—

1. In a vapor-burner, the combination, with the base-plate and laterally-arranged needle-valve, of a bent mixing-tube having its upright portion mounted to rotate in the base-plate, whereby its lower and laterally-projecting part may be swung horizontally into and out of line with the needle-valve, substantially as described. 3c

2. In a vapor-burner, the combination, with the base-plate and laterally-arranged needle-valve, of a bent mixing-tube having its upright portion mounted to rotate in the base-plate, and its laterally-projecting lower portion provided with an external deflecting- 35 shield, substantially as described. 40

3. The combination of the base-plate A, provided with a circular aperture, the mixing-tube D, fitted to rotate therein, and the washer D', applied to the tube above the base-plate, 45 substantially as and for the purpose set forth.

J. BENNETT WALLACE.
GARSON MYERS.
